(57) **CLAIM**

The ornamental design for a motorized scooter, as shown and described.

DESCRIPTION

FIG. 1 is a front view of our new design for a motorized scooter;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a perspective view thereof; and,

FIG. 8 is another perspective view thereof.

The broken lines are for the purpose of illustrating portions of the article that form no part of the claim. The shading lines shown in the drawings represent the approximate three-dimensional contour of the design, and are not intended to indicate surface decoration.
